UNITED STATES PATENT OFFICE.

CASPER ZIMMERMAN, OF HAZEL, SOUTH DAKOTA.

FUEL-FEEDING DEVICE FOR STRAW-BURNING KILNS AND FURNACES.

No. 796,887.

Specification of Letters Patent.

Patented Aug. 8, 1905.

Application filed September 29, 1904. Serial No. 226,503.

To all whom it may concern:

Be it known that I, CASPER ZIMMERMAN, a citizen of the United States, residing at Hazel, in the county of Hamlin and State of South Dakota, have invented certain new and useful Improvements in Fuel-Feeding Devices for Straw-Burning Kilns and Furnaces; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to an apparatus designed for feeding straw, cornstalks, hay, sage-brush, and material of like nature used as fuel to the fire-chambers of brick and other kilns and to furnaces in which fuel of this character is employed.

The invention has for its object the provision of a simple and inexpensive apparatus so constructed and arranged relative to the kiln or furnace as to insure a uniform supply of fuel being supplied to the fire at all times and at the same time to cause a perfect combustion.

To these ends and to such others as the invention may pertain, the same consists in the peculiar construction of the apparatus and in its arrangement relative to the combustion-chamber of a kiln or furnace, all as will be more fully hereinafter described, shown in the accompanying drawings, and then specifically defined in the appended claim.

The invention is clearly illustrated in the accompanying drawings, which, with the letters of reference marked thereon, form a part of this specification, and in which drawings similar letters of reference indicate the same parts throughout the several views, and in which—

Figure 1 is a perspective view of my invention, the same being shown as applied to a brick-kiln. Fig. 2 is an end elevation of the same. Fig. 3 is an enlarged detail in perspective of a portion of one of the endless chains, showing one form of tine employed. Fig. 4 is a like view showing a modified form of tine. Fig. 5 is a top plan view of the tine shown in Fig. 4, and Fig. 6 is an enlarged detail view of another slightly-modified form of tine.

Reference now being had to the details of the drawings by letter, A designates a kiln, which may be of any of the well-known forms such as are adapted for use in burning brick, baking pottery, &c., and which are provided with combustion-chambers extending in lines

beneath or through the lower portion of the structure.

B B are the upright posts or supports, and C C portions of a framework structure which is erected over the kiln. This framework may be constructed of iron pipes, as shown, or may be of any other material and of such form as may be found to be best adapted to the purpose.

A driving-shaft D, driven from any source of power, is mounted in suitable bearings α on the uprights B B of the frame, and to said shaft are keyed sprocket-wheels E E, spaced apart, as shown clearly in Fig. 1 of the drawings. A second set of sprocket-wheels (designated in the drawings by letter E^x) is mounted upon a shaft E² near the openings into the kilns. Sprocket-wheels F F are journaled loosely upon a shaft G, which is positioned parallel to the shaft D, but slightly above the same, and similar sprocket-wheels H H are loosely journaled upon a shaft H', while the sprocket-wheels I I are similarly mounted upon the shafts I'. It will be observed upon reference to Fig. 2 of the drawings that the wheels E^x and I are positioned, respectively, near the front and rear faces of the kiln and adjacent to the openings therein. Endless sprocket-chains J J pass about said pulleys in the manner disclosed in the drawings, and said chains carry at intervals tines or fingers K K, which may be of any length or shape found best adapted for the purpose of drawing fuel into the openings of the kilns. It will be noted that the sprocket-chains in passing around the several pulleys will pass longitudinally through the combustion-chambers of the kilns.

In use rotary motion is imparted to the driving-shaft D and the sprocket-chains J are caused to travel through the combustion-chambers of the kiln from front to rear. Straw, cornstalks, hay, or other material used as fuel which is thrown into contact with the chains will be caught by the tines upon the chains and carried into the combustion-chambers and will be carried slowly through the said chambers, the speed being governed by the rate of rotation imparted to the driving-shaft D, and which should be so regulated as to allow the burning fuel to be fully consumed within the chamber. By this method of supplying straw or other material of like nature to the fire a uniform and perfect combustion is insured and the greatest possible degree of heat from a given quantity of fuel is insured.

By the provision of the apparatus shown and described it will be observed that straw of various kinds or grain may be utilized as a cheap and efficient fuel, and which may be caught by the tines and drawn through the combustion-chamber without leaving any residue of ashes upon the floor of the chamber, and the speed at which it is desired to feed the fuel may be regulated according to the consistency of the straw.

Having thus fully described my invention, what I claim to be new, and desire to secure by Letters Patent, is—

A kiln or furnace having combustion-chambers arranged parallel to one another and extending through the kiln, a framework positioned about the kiln and having parallel

and horizontally-disposed tubular portions, sprocket-wheels loosely journaled upon said tubular portions, sprocket-chains mounted upon said sprocket-wheels and adapted to travel over the top of the kiln and through the combustion-chambers, forked tines secured to said chains at intervals and at right angles thereto and adapted to draw fuel through said combustion-chambers, as set forth.

In testimony whereof I hereunto affix my signature in presence of two witnesses.

CASPER ZIMMERMAN.
